UNITED STATES PATENT OFFICE.

RALPH EMERSON, OF ROCKFORD, ILLINOIS.

IMPROVEMENT IN CLOTHES-PINS.

Specification forming part of Letters Patent No. 127,751, dated June 11, 1872.

To all whom it may concern:

Be it known that I, RALPH EMERSON, of Rockford, in the county of Winnebago and State of Illinois, have invented certain new and useful Improvements in Clothes-Pins, of which the following is a specification:

The object of my invention is cheaply and simply to manufacture a clothes-pin which can readily be placed upon or released from the line without injury to itself or to the clothes upon the line.

In the accompanying drawing, Figure 1 is a perspective view of my improved pin, about to be placed upon or removed from the line; Fig. 2, a like representation of the same when in position upon the line; Fig. 3, a view in elevation of my improved pin partly formed. Fig. 4 represents a similar view of a finished pin. Fig. 5 represents a transverse section thereof in the line *x x* of Fig. 4, as hereinafter described.

In making my pins I take an oblong block, A, and make an oblique cut, *a b*, in one end thereof, extending inward from one edge past the center line of the block. I then make a similar cut, *c d*, intersecting the first one, as shown in the drawing. I then make a central longitudinal cut, *e f*, passing through the two oblique cuts at their point of intersection. The jaws and legs of the pin are formed by these three cuts, the triangular space *i* being the part which clasps the line; thus forming

the pin in a very simple, cheap, and expeditious manner.

The legs may be made elastic by thinning them, as shown in Fig. 4.

The jaws *h h* are beveled at *j j* by a chisel, (see Fig. 5,) and form straight inclines, that enable the pin to be readily removed and placed in position by applying the pin sideways to the line, as shown in Fig. 1.

Heretofore the jaws of the pin have been rounded for a similar purpose, and were formed by a burring-tool, which is not so easily done nor so effectual in operation as a straight bevel or incline, which can be made by one stroke of a chisel.

I am aware that clothes-pins heretofore have been formed by slotting a block longitudinally, by thinning its edges, and with notches of various forms; and do not, therefore, broadly claim a pin having these features.

What I claim as my invention is—

A clothes-pin formed by making two intersecting oblique cuts, with a third central longitudinal cut intersecting the other two at their point of junction, substantially as set forth.

In testimony whereof I have hereunto subscribed my name.

RALPH EMERSON.
